UNITED STATES PATENT OFFICE.

MATT K. MAHAN, OF HARTSELLS, ALABAMA.

PANEL FENCE.

SPECIFICATION forming part of Letters Patent No. 729,779, dated June 2, 1903.

Application filed October 9, 1901. Serial No. 78,123. (No model.)

To all whom it may concern:

Be it known that I, MATT K. MAHAN, a citizen of the United States, residing at Hartsells, in the county of Morgan and State of Alabama, have invented a new and useful Panel Fence, of which the following is a specification.

The invention relates to improvements in fences.

10 The object of the present invention is to improve the construction of fences and to provide a simple and comparatively inexpensive one of a portable character, capable of being quickly set up for use and adapted to be conveniently carried.

15 A further object of the invention is to provide a fence of this character which will dispense with numerous posts or stakes that are driven or otherwise mounted in the ground.

20 The invention consists in the construction and novel combination and arrangement of parts hereinafter fully described, illustrated in the accompanying drawings, and pointed out in the claim hereto appended.

25 In the drawings, Figure 1 is a perspective view of a portion of a fence constructed in accordance with this invention. Fig. 2 is a detail sectional view illustrating the manner of securing the panels to the top wire.

30 Like numerals of reference designate corresponding parts in both figures of the drawings.

35 1 1 designate similar panels, designed to be constructed of any suitable material which will render them light and portable, and each panel is composed of end uprights or bars 2 and connecting planks or rails 3, which may be of any desired number and which are suitably secured to the end bars or uprights.

40 The panels which rest upon the ground are connected by bottom ties 4, of wire or other suitable material. The wire of which the tie is constructed is arranged on the lower ends of the uprights or bars, as clearly illustrated 45 in Fig. 2, and its ends are suitably secured together, preferably by twisting. Any number of panels may be arranged between two end posts or supports 5, which may consist of trees or may be formed by ordinary fence-

50 posts. These posts 5 are firmly set in the ground and in practice will be placed at a

distance of about one hundred yards apart. The uprights or bars 2, adjacent to the posts or supports 5, are secured at their lower ends to the same by bottom ties 6, constructed of 55 wire and arranged similar to those heretofore described.

The panels are supported and prevented from swaying laterally by means of a top wire 7, stretched from one post or support 5 to 60 the other and suitably secured to the same, preferably by being passed around the posts or supports 5 and twisted on the body portion of the supporting-wire. The upper ends of the bars or uprights 2 of the panels are provided with narrow vertical slots 8 for the reception of the supporting-wire 7, which is secured in the slots by means of removable pins or keys 9, arranged at an inclination, as clearly shown in Fig. 2, to prevent them from 70 being accidentally jolted out of the perforations of the uprights or bars. The removable pins or keys present inclined portions to the horizontal top wires 7 and hold the same against the end bars or uprights at the bottoms of the slots. These slots or bifurcations, which extend downward from the top of the bars or uprights, may be arranged in any suitable manner, but are preferably disposed in alinement, as shown, and by securing the 80 upper ends of the uprights or bars to the top wire in this manner the panels may be readily detached and numerous wire ties and analogous devices are dispensed with.

It will be seen that the fence, which is simple and comparatively inexpensive in construction, may be rapidly erected, that the panels, which may be constructed of any suitable material, can be conveniently carried or hauled from one place to another, and that 85 the top wire when stretched to the proper tension is adapted to support the panels against lateral movement. It will also be apparent that by constructing a fence as herein shown and described the digging of numerous post-holes and the driving of stakes are 90 obviated.

What I claim is—

In a fence, the combination with a horizontal supporting-wire, of means for supporting the same, a removable panel having end bars provided with slots to receive the sup-

porting-wire and with inclined transverse perforations, and removable keys inserted through the perforations above and in contact with the supporting-wire, whereby the keys 5 will be maintained at an inclination to prevent their accidental escape and to maintain the wire securely in the slots.

In testimony that I claim the foregoing as my own I have hereto affixed my signature in the presence of two witnesses.

MATT K. MAHAN.
